INVENTOR

Jacob L. Orent

BY
Wm. G. Lindstrom
ATTORNEY

UNITED STATES PATENT OFFICE.

JACOB L. ORENT, OF NEW YORK, N. Y.

GARMENT.

Application filed January 7, 1925. Serial No. 989.

To all whom it may concern:

Be it known that JACOB L. ORENT, citizen of the United States, residing at New York city, in the county of Kings and State of New York, has invented certain new and useful Improvements in Garments, of which the following is a specification.

This invention relates to an improvement in women's wearing apparel, and more particularly, is directed to a fur outer garment of novel construction which may be worn either as a coat or jacket as desired.

Women's fur garments are made either in the form of three quarter or full length coats, or jackets and in order that the wearer may be suitably provided for various climatic conditions during the various seasons of the year, and to permit various modes of dress, it has been found desirable for the wearer to have one of each of such garments.

An object of the invention is to provide a single garment of the character described formed of detachable members which when assembled simulate a single-piece garment and which may be easily converted and selectively used either as a jacket or coat as desired.

A further object of the invention is to provide a garment of the character described which is simple in construction, neat in appearance, relatively inexpensive to manufacture and practical and efficient to a high degree for the purpose described.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention,

Fig. 1 is a perspective view of an assembled women's fur garment embodying the invention;

Fig. 2 is a cross-sectional view taken on line 2—2 in Fig. 1;

Fig. 3 is a cross-sectional view similar to Fig. 2 showing garment members in position ready to be assembled;

Fig. 4 is a cross-sectional view showing the placket or fent of the jacket in closed position; and

Fig. 5 is a fragmentary portion of the garment shown in Fig. 1 viewed from the interior side, with the detachable members separated and exposed to show the fastening means.

Referring in detail to the drawing, 10 denotes a fur garment embodying the invention which is constructed to simulate a one-piece coat. The garment 10 comprises a jacket or short coat which may have the usual sleeves 11^a and a collar 11^b, and a separable skirt 12 which is secured by its upper edge portion or tongue 12^a to the lower edge portion 11^c of the jacket 11 by any suitable quick detachable means, such as snap fasteners 13.

The coat 10 may also be provided with any well known front closure means including buttons 14 or the like. The jacket 11 and skirt 12 each may have fur or the like material on their exterior sides 11^a, 12^a respectively, and linings 15, 16 respectively, constructed in the well known manner may be provided on the interior sides of said jacket and skirt.

The jacket portion 11^c is preferably made to have a placket or fent 17 for receiving the skirt portion 12^a between edge flaps 11^e and 15^a of the exterior material 11 and lining 15 respectively as shown in Figs. 2, 3 and 5. Thus, the means for detachably securing the skirt 12 to the jacket 11 are completely hidden from view by being secured on the interior sides 18, 19 of the flaps 11^e, and 15^a, and the corresponding sides 20, 21 of skirt portion 12^a, said sides being formed of a reinforcing material extending from the jacket and skirt structure as shown in Figs. 2, 3 and 4. The material 11^e and lining 15 are preferably turned in as at 11^f and 15^b so that the reinforcing material does not show when the garment is in use.

Snap fastening 13 may be arranged in a single row, but double rows as shown in the drawing are preferably provided to uniformly and substantially hang the skirt 12 from the jacket.

When it is desired to use the invention as a coat, the upper portion 12^a of the skirt 12 is inserted up into the placket 17 between the flaps 11^e and 15^a as shown in Fig. 3 and

- the fasteners 13 on the interior side of said flaps are brought into engagement with those in skirt portion 12^a as shown in Fig. 2. The garment will then have the appearance 5 shown in Fig. 1, and may now be used as a one-piece coat, the detachable securing means being completely hidden when the garment is viewed from the exterior or interior side thereof.
- 10 To convert the garment into a jacket, the skirt is simply detached in the well known manner and the flaps 11^a and 15^a may be secured together by the fastening as shown in Fig. 4.
- 15 It will thus be seen that there is provided a device in which the several objects of this invention are achieved and which is well adapted to meet the conditions of practical use.
- 20 As various possible embodiments might be made of the above invention, and as various changes might be made in the embodiment above set forth, it is to be understood that all matter herein set forth or shown in 25 the accompanying drawing is to be interpreted as illustrative and not in a limiting sense.
- Having thus described my invention, I claim as new and desire to secure by Letters 30 Patent:—
1. A convertible garment of the character described comprising a jacket having a lining, a skirt, reinforcing means incorporated within the garment structure, a placket 35 formed by the edge portions of the exterior material of the jacket, and the lining for receiving the upper edge of the skirt, said means extending into said placket, and fasteners on the portions of said means in said placket for detachably securing the skirt to the jacket, said fasteners constructed to interlock for holding the placket closed when the skirt is detached from the jacket.
2. A two piece garment of the character described comprising a jacket having a lining, and skirt arranged to be detachably secured to the jacket for converting same into a coat, a placket formed along the lower edge portions of the jacket between the outer material of the jacket and the lining for receiving the upper edge portion of the skirt, a plurality of rows of fastening members mounted on the interior side of the placket and corresponding rows of fastening members on the said edge of the skirt portion for engaging with the first mentioned fastening members, said jacket and skirt when assembled simulating a single piece garment as viewed from either the interior or exterior side thereof.
3. A garment adapted to be selectively converted into a coat or jacket comprising a jacket having a lining, a skirt, a placket formed by the edge portions of the outer material of the jacket and the lining for receiving the upper edge of the skirt, and means on the jacket and lining portions of the placket for detachably securing the skirt to the jacket, said means constructed to interlock for holding the placket closed when the skirt is detached.
- In testimony whereof I affix my signature.

JACOB L. ORENT.
